7 Claims. (Cl. 340—174)

This invention relates to magnetic core register devices, and more particularly to an improved register circuit of the type employing magnetic cores.

Magnetic cores offer certain advantages when used as storage, logical and memory devices in electronic data handling systems since they are small, require low-operating power and can store information for extended periods of time without subsequent power input and loss in standing. Binary data can be stored by these magnetic cores due to the fact that the cores may be magnetically saturated in either of two directions and after the force creating the saturation is removed, a remanent flux exists within the core whose direction is dependent on the direction of the last applied magnetomotive force. The magnetic saturation is accomplished by passing a current pulse through a winding on the core.

Progressively moving information from the input circuit to the output circuit along a chain formation of magnetic cores at a selected rate and at a selected time defines the operation and the function of a shift register or as it is sometimes known, a magnetic delay line. This information transfer or switching is achieved by the application of a current pulse to a winding on the magnetic core, usually referred to as the advance or drive winding, so as to produce a remanent flux within the core of a direction opposite to the pre-existing flux direction. During the change in the flux direction, a voltage pulse is induced in another winding, namely the output winding. The output winding is connected to a winding on the core of the next succeeding magnetic core in the chain and the pulse produced across the output winding of the first core will be applied to the input winding of the next succeeding core. If this induced voltage pulse is greater than a certain selected value, it will produce a magnetomotive force on the second core sufficient to change the residual flux direction of the second core, provided, however, that the force creates a flux opposite in direction to the remanent flux existing on the second core before the application of the induced voltage. It should be noted that where the saturation current is applied to produce a flux in the same direction as the residual flux already existing on the core, the flux change thusly produced is small and hence the voltage induced at the output winding of that core is less than the minimum required to saturate the next succeeding core.

Since in operation, the information or data is transferred from one core to the next, each core must have an advance winding which, when a current pulse is applied to it, saturates the core in one direction in order to advance the information toward the output. If the advance pulse creates a flux saturation opposite in polarity to that existing in the core before its application, an output voltage pulse is induced on both the output winding and the input winding of that core. Since the output winding of one core is connected to the input winding of the next core this induced voltage at the input winding will be coupled back to the output winding of the preceding core and produce therein undesirable results. In order to overcome this effect, an asymmetrically conductive device may be shunted across the input winding of a core and this shunt device in conjunction with a similar device series connected between the input winding of one core and the output winding of the preceding core, are suf-

2

ficient to prevent the preceding core from saturating due to the voltage pulse induced on the input winding of the succeeding core. However, even though the preceding core is not saturated, nor is its residual flux direction changed, the undesired voltage that appears across the output winding of the preceding core with the aforementioned blocking or decoupling circuit, a sufficient magnetomotive force is generated to alter the magnitude of the residual flux and, thereby prevent its assuming the flux condition corresponding to one or the other of its stable states. It is this slight change in residual flux that decreases the "signal" to "no signal" ratio and accounts for one of the main difficulties in the prior art circuitry.

An object of this invention is to provide an excellent magnetic core shift register circuit, which will have a relatively high "signal" to "no signal" ratio and maximum stability of operation.

Another object is to provide an electrically simple, practical, efficient, inexpensive and stable magnetic core shift register circuit.

Other objects and advantages will be apparent from the following description of an embodiment of the invention, and the novel features thereof will be particularly pointed out hereinafter in connection with the appended claims.

FIG. 1 is a graph, somewhat idealized of the hysteresis loop for a magnetic material used in the fabrication of magnetic cores;

FIG. 2 is a schematic diagram of a magnetic core shift register circuit before this invention is applied thereto; and

FIG. 3 is a schematic diagram of an improved magnetic core shift register employing the embodiment of this invention.

Magnetic memory cores are fabricated from magnetic materials, as for example, molybdenum-permalloy or manganese-magnesium ferrite, which exhibit the desired hysteresis loops as illustrated in FIG. 1. The magnetic properties of each core used in shift registers core characterized by the loop of FIG. 1, wherein the horizontal axis represents the magnetizing force H applied to the core and the vertical axis represents the flux density B . B_m is the maximum value of the flux density in the core during the application of a saturating magnetomotive force, while B_r is the remanence flux density to which the induction returns when the magnetomotive force is removed. The coercive force H_c is the magnetizing force required to return the core to zero magnetic induction after the application of a saturating magnetomotive force in the opposite direction. It should be noted that two stable magnetic states exist for the core and they occur at the intersection of the hysteresis loop and the vertical B axis, that is, where the magnetomotive force is removed or equal to zero after the application of a saturating magnetomotive force. A large positive magnetizing force or pulse will leave the core with a positive remanent or residual magnetism as represented by the state "1" while a similarly large negative magnetizing pulse will leave the core in the state represented by "0." This bistable characteristic of the core makes it possible to store a binary digit or information.

The illustrated magnetic core shift register or delay line comprising a chain formation of substantially identical magnetic core is illustrated in FIG. 2, wherein four cores are shown, though more or less cores may be employed. The cores may be of any suitable cross-sectional shape, preferably toroidal, each core having wound thereon three separate and distinct windings, which are an input winding N_i , an output winding N_o and an advance winding N_a or N_b . The advance windings N_a and N_b are provided on alternate cores in the chain and alternate

windings are connected in series, the advance windings of alternate cores being joined so that the even core advance windings N_b are in series with each other, and the odd core advance windings N_a are in series with each other, and each group of alternate advance windings being pulsed independently of the other group. The first core of the chain receives the external input pulse applied across its input winding N_i . Each core output winding N_o is connected to the input winding of the next succeeding core in the chain through an asymmetrically conductive device such as a diode or rectifier 5 and a resistor 6, with a second diode 7 in shunt across the input winding N_i of the succeeding core and the resistor 6. The advance windings N_a and N_b are wound around the cores in such a direction as to energize the cores to the "0" state of magnetization when rectangular current pulses are applied to the advance circuits 8 and 9.

Initially all the cores are in the "0" state and the first pulse to appear in time is the i_1 advance pulse which merely creates in the odd cores magnetization from "0" to $-B_m$. Since this is a relatively small change in flux only a small voltage will be developed on the output windings of the odd cores which is of an insufficient magnitude to affect the flux state of the next succeeding core to which it is coupled.

The signal input to the first core may occur at any time other than in coincidence with the advance pulse i_1 . The most commonly employed time-cycle, that is, one in which the signal input occurs at the same time as i_2 advance pulse, is as shown in FIG. 2. The input winding N_i of each core is wound in a direction so that a positive input pulse of sufficient magnitude will energize the core to the "1" magnetic state. An input signal is now applied to the N_i windings of core 1 and the core changes from "0" to "1" state of magnetization. This rapid change of flux in core 1 induces a voltage across the output windings of that core, which voltage tends to drive a current toward the input winding N_i of core 2 in the direction of high resistance through diode 5 so that the current reaching the input windings N_i of core 2 is of an insufficient magnitude to change the magnetic state of core 2. Advance pulse i_2 now occurs, but, since the even cores are in the "0" state they remain in that state and no change occurs. The next pulse to appear in the time cycle is advance pulse i_1 , which energizes core 1 from its previous "1" state to the "0" state of magnetization. This rapid flux change induces a voltage across the output winding N_o of that core in the direction of low resistance or forward propagation through diode 5 and the resultant current pulse thereby applied to the input winding N_i of core 2 drives the core 2 from "0" state to the "1" state of magnetization. Advance pulse i_2 similarly advances the "1" state from core 2 to core 3, and advance pulse i_1 thereafter advances the "1" state from core 3 to core 4 until the output stage is reached.

It should be noted that the voltage induced in the input winding of any core, as for example, core 2, when the core magnetization state is changed from "1" to "0" by the advance pulse i_2 , drives a current in a forward propagating manner through diode 5 towards the output winding N_o of the preceding core. This back current is in a direction to drive the preceding core to the "1" state but diode 7 which is in shunt across the input winding N_i short circuits a portion of this back signal. Resistor 6 is included in this shunt circuit to dissipate this energy and to introduce some impedance in this portion of the circuit. The magnetic state of the preceding core nevertheless is altered and the resultant change follows the hysteresis loop a short way up from the "0" state towards H_c and then falls back *almost* all the way to the "0" state again. The fact that it does not fall *all* the way back, and therefore causes a slight algebraic increase in the value of the "0" state, resulting in a decrease in the "signal" to "no signal ratio" is one of the main difficulties with magnetic core shift registers.

In the embodiment of this invention, as illustrated in FIG. 3, a chain formation of magnetic cores, similar to those described hereinbefore, is employed, though only three cores of the chain are shown. In order to further reduce or eliminate the back signal generated at the input winding of one core from appearing at the output winding of the preceding core, an additional winding N_m is wound about each core except the first core, as for example, cores 2' and 3'. Leads 10' and 11' connect the shunt side 12' of the input winding and the output winding N_o of the preceding core. This connection is made so that the voltage induced in this additional winding N_m by currents in the other windings on the same core opposes any back signal from the input winding of any core after the first one which tends to be set up in winding N_o on the preceding core. It now however, becomes necessary to increase the number of turns of the input winding N_i to form a larger winding N_i' on all cores after the first one, in order that the total signal being advanced from a preceding core to the next core in the chain is not diminished by the opposing added windings N_m which might otherwise prevent sufficient magnetization of the next core to effect a change of its magnetic state. It has been found satisfactory to make such an increase in the total number of turns of the N_i input winding by an amount equal to the turns in the additional winding N_m , so that the resultant magnetizing signal received, for example, from core 1' by core 2' is the same as before the addition of the N_m windings. The turns that were added to the input winding N_i of core 2' to give winding N_i' do not themselves produce an additional voltage at the output winding N_o which might cancel out all the desirable effects introduced by the new winding N_m since their induced voltages are in opposition, because any adverse voltages induced across the additional turns on N_i' are shunted across winding N_i' by diode 7' which is connected across the total windings N_i' . Since the voltage induced across the additional winding N_m is not shunted, the net gain or improvement in "signal" to "no signal" ratio is approximately proportional within limits to the voltage across winding N_m . It has been found that the addition of these extra windings N_m to buck out the back signal, increases the operational stability of the shift register and increases the "1" to "0" signal ratio by at least 6:1.

It will be understood that various changes in the details, materials and arrangements of parts, which have been herein described and illustrated in order to explain the nature of this invention, may be made by those skilled in the art within the principle and scope of the invention as expressed in the appended claims.

We claim:

1. A shift register comprising a chain of information storing cores stably magnetizable selectively in each of two directions, input, output and advance windings on each core, the output winding of each core except the last connected in series with the input winding of the next successive core, a blocking winding on each core after the first core, connected in series with the series connected input winding on the same core and the output winding on the preceding core and having turns in a direction to oppose the said input winding with which it is connected, means connected with each set of said three series connected windings and cooperating with said blocking winding for blocking the transfer of energy from said input winding back to the output winding on the preceding core with which it is in series but insufficient to prevent a change in magnetization of the core on which the blocking winding is located.

2. The register according to claim 1, wherein said means includes one rectifying means in series with all three windings of said series connected windings and another rectifying means in shunt across said input winding.

3. In a shift register of the type having a chain of information storing cores stably magnetizable selectively in each of two directions with input, output and advance

windings on each core and with the output winding of each core except the last, connected in series with the input winding of the next successive core, with one rectifying means in series with both series connected windings and another rectifying means in shunt across the input winding that is in series with the output winding, that improvement which comprises a blocking winding on each core after the first core, connected in series with the output winding on the preceding core and the input winding on the same core, and in series with said one rectifying means and having turns in a direction and in number to block the transfer of energy from said input winding back to the output winding on the preceding core with which it is in series, but permitting a change in magnetization of the core on which the input and blocking windings are located in response to a pulse signal from the output winding of the preceding core.

4. In a shift register of the type having a chain of information storing cores stably magnetizable selectively in each of two directions with input, output and advance windings on each core and with the output winding of each core except the last, connected in series with the input winding of the next successive core, with one rectifying means in series with both series connected windings and another rectifying means in shunt across the input winding that is in series with the output winding, that improvement which comprises winding means responsive to current flow between each output winding and the input winding with which it is in series, for blocking the transfer of energy from said input winding back to the output winding with which the input winding is connected, but ineffective to prevent a change in magnetization of the core having said input winding.

5. In a shift register of the type having a chain of information storing cores stably magnetizable selectively in each of two directions, each core having an input, output and advance windings, the input winding of each core after the first and the output winding of the immediately preceding core of the chain beginning with the first core being in series circuit, and wherein asymmetrically conductive elements are operative on the series circuit for forward signal propagation and another asymmetrically conductive element in shunt with said input winding to substantially block transfer of energy from the input winding of the succeeding core back to the output winding of the preceding core in response to change in magnetization of the core supporting the input winding, the improvement which comprises a "back signal" blocking winding supported on the same core as said input winding

5
after the first core wound in opposition to said input winding and connected in series with said input winding between the output winding of the preceding core and said shunting asymmetrically conductive device, and having a number of turns to allow a change in magnetization of the core on which said input and said blocking windings are located in response to a pulse signal from the output winding of the preceding core, but having turns to block the transfer of energy from said input winding back to the output winding of the preceding core not otherwise shunted by the asymmetrically conductive element.

6. In a shift register of the type having a chain of information storing cores stably magnetizable selectively in each of two directions, input, output, and advance windings on each core and having N_i , N_o , and N_a turns respectively, that improvement for each core after the first, which comprises a first loop circuit having in series connection therein the output winding of the preceding core, one rectifying means, said input winding, N_m additional turns on said input winding, and a blocking winding having N_m turns in a direction to oppose said input winding, and wound on the same core, a second loop having in series therein said input winding and additional turns and another rectifying means whereby the transfer to the output winding of the preceding core of the voltage induced across said input winding and additional turn will be blocked, but any voltage induced on the output winding of the preceding core will be transferred to said input winding.

7. The improvement according to claim 6, wherein said second loop also contains in series connection therein a resistance element.
